UNITED STATES PATENT OFFICE.

JOHN R. DEAN, OF WESTMINSTER, ENGLAND.

BOOT.

SPECIFICATION forming part of Letters Patent No. 310,389, dated January 6, 1885.

Application filed August 15, 1884. (No model.) Patented in France March 19, 1884, No. 161,052.

To all whom it may concern:

Be it known that I, JOHN RICHARD DEAN, of the Strand, in the city of Westminster, England, boot-maker, have invented certain new and useful Improvements in Knee, Thigh, and other High Boots, of which the following is a specification.

The object of this invention is to overcome certain inconveniences attendant upon the use of knee, thigh, and other high boots. The great objection to these boots is the difficulty in getting them on and off, especially when wet, and it is well known that soldiers, for instance, on active service, are often obliged to keep their boots on for days if they get wet—a course which, to say the least, is very prejudicial to the health of the soldier, and one very likely to incapacitate him from service by reason of sore feet. A further objection to these boots is that on account of the difficulties in getting them on and off they are obliged to be made larger in the heel than is necessary, and consequently they are ill-fitting and very uncomfortable to wear. These difficulties and objections are well known and appreciated, and the object of my invention is to overcome them. To this end, and especially with a view to enable such boots to be made smaller in the heel than heretofore, and yet permit the easy entrance of the foot, I remove from a convenient part of the boot a suitably-shaped piece or pieces, which I replace by a spring or springs, of india-rubber or other suitable elastic fabric, or by a gusset or gussets of leather or other suitable material; and in order to protect such spring or gusset from the abrasion to which, owing to the rough use of such boots, it would be liable, I employ a flap of leather, which I secure outside of the boot for the protection of the said spring or gusset. In some cases I attach to the said flap an instep-strap to be secured by buckles or studs to the heel of the boot.

Now, in order that my invention may be clearly understood, I will describe it with reference to the drawings hereunto annexed, in which—

Figure 1 is a side view of a knee-boot with the spring or gusset applied thereto, Fig. 2 being a section of the boot at the part where the spring is inserted. Fig. 3 is a side view of the boot with the instep-strap applied thereto.

A is the upper, and B the leg, of the boot. From any convenient part of the boot, but

preferably at the point marked C, I cut an oval, semicircular, or other suitably-shaped piece, as indicated by the dotted line, and in place of the piece thus removed I insert a spring of vulcanized india-rubber or other suitable elastic material, or a gusset of thin leather or other material, as shown at a, Fig. 2. In general the spring or gusset a will consist of some water-proof material, and will be secured to the boot in such a manner as to render the boot water-proof; but I do not wish to confine myself to the use of water-proof material, as for hot climates it may be desirable to employ some ventilating material; but for general use I prefer the rubber spring, as its elasticity will cause the boot to fit better round the instep.

In order to preserve the spring or gusset from abrasion and to cover the orifice C, I employ a flap of leather, D, which I secure outside the boot by sewing on three sides, as indicated in the figure. This flap will be sufficiently loose to allow for the stretching while the boot is being put on, but will lie flat against the boot when worn.

F, Fig. 3, is the instep-strap, permanently attached to the flap D in any suitable manner, as by being placed under the flap and secured thereto by stitching along the edges of the strap, as indicated by dotted lines in Fig. 3. This strap is secured to the heel of the boot by a stud or studs, b, as shown, or by a buckle, or in any other convenient manner, and it serves to hold the flap close over the spring or gusset. When riding, this strap may be loosened or unfastened, so that should the rider be thrown the boot will be free to come off should his foot catch in the stirrup.

Having now described my invention and explained the manner of carrying the same into effect, what I desire to claim is—

1. In knee, thigh, and other high boots, the combination of a spring or gusset, as a, with a flap, as D, substantially as and for the purpose set forth.

2. In knee, thigh, and other high boots, the combination of a spring or gusset, as a, flap, as D, and instep-strap, as F, substantially as set forth.

JOHN R. DEAN.
